UNITED STATES PATENT OFFICE.

FREDERICK J. KALTEYER, OF PHILADELPHIA, PENNSYLVANIA.

RAZOR-SHARPENING DEVICE.

1,230,717.

Specification of Letters Patent. Patented June 19, 1917.

Application filed March 16, 1916. Serial No. 84,569.

To all whom it may concern:

Be it known that I, FREDERICK J. KALTEYER, a citizen of the United States, residing in the city and county of Philadelphia, 5 State of Pennsylvania, have invented a new and useful Razor-Sharpening Device, of which the following is a specification.

My present invention relates to a sharpening device which is especially adapted for 10 the sharpening of razor blades of all kinds, although it may be employed to sharpen the cutting blades of knives or other tools.

With the above in view, my invention consists of a sharpening machine, which is 15 adapted to be employed to sharpen the blades of the old fashioned razors and also to sharpen the blades of safety razors or any type of removable razor blade.

It further consists of a novel construction 20 of a razor sharpening device in which a blade holder is provided with a resilient shank which is pivotally mounted to provide both a rocking adjustment and an adjustment to and from the sharpening rolls 25 in a longitudinal plane between the rolls so that the position of the blade with reference to a roll may be varied and also its resistance to flexure.

Other novel features of construction and 30 advantage will hereinafter more clearly appear in the detailed description of my invention.

For the purpose of illustrating my invention, I have shown in the accompanying 35 drawings a typical embodiment which will give satisfactory and reliable results in practice, but it is of course to be understood that such embodiment is typical only and that the various instrumentalities of which my 40 invention consists can be variously arranged and organized, and that my invention is not limited to the precise arrangement and organization of these instrumentalities as herein shown and described.

45 Figure 1 represents a perspective view of a razor sharpening device embodying my invention.

Fig. 2 represents an end elevation of Fig. 1, certain parts being shown in section.

50 Fig. 3 represents a side elevation, partly in section, of a portion of my device.

Fig. 4 represents an end elevation of certain parts of the device, showing them in a different relation with respect to each 55 other from that seen in Fig. 2.

Fig. 5 represents a diagrammatical view of the automatic stop mechanism of the motor.

Similar numerals of reference indicate corresponding parts in the figures. 60

Referring to the drawings:

1 designates a base or support, upon which is mounted, in any desired manner, a motor 2, which for purposes of illustration, I have shown as consisting of an electric motor having the conductors 3 and 4 connected with the battery 5 or other source of electrical supply. 6 designates the motor shaft on which is mounted the pinion 7, which meshes with a gear 8 mounted on a shaft 9, and said gear 8 meshes with a gear 10 mounted on a shaft 11. The stationary shafts 9 and 11 have their inner ends fixed in any desired manner on the casing of the motor 2, and are arranged parallel with respect to each other. 70

The gear 8 is fixed to a roll 12 loosely mounted on the shaft 9, and retained thereon by means of a set collar 13, which is secured to the shaft, in the present instance, by means of a pin 14 passing through the collar 13 and the shaft 9. A portion of the periphery of the roll 12 is cut away, as indicated at 15, so as to form a shoulder 16. 17 designates a strip of leather or other suitable material which has been properly treated to form a surface which will have a sharpening effect on the blade with which it comes in contact, and as will be apparent, either a grinding or a stropping surface may be 80 provided. 85

The strip of material 17 extends from the shoulder 16 to the point 18. 19 designates a roll to which the gear 10 is fixed, and said roll conforms in construction and contour to the roll 12 and is mounted on the shaft 11, a set collar 20 being employed to retain the roll 19 on the shaft 11. 21 designates a strip of leather or other suitable material secured to the periphery of the roll 19 and conforming in construction and contour to the strip of material 17 on the roll 12. 90 95

22 designates a threaded rod fixed to the casing of the motor 2 and extending through the slot 23 of the flange or angle arm 24 of a bracket 25, and in order to maintain the bracket 25 in its vertically adjusted position, a thumb nut 26 is provided which engages the threads of the rod 22. The bracket 25 comprises an arm which extends for 100 105 110

wardly and which is provided at its forward end with a threaded rod 27 having the thumb nut 28. The rod 27 passes through the slot 29 in a blade holder or clamping device 30, which consists of a resilient arm 31 which carries at its lower end the clamping jaws 32 and 33. As illustrated, the jaws are formed by slotting the lower end of the blade holder 30 in order to provide two yielding clamping jaws.

10 A bolt 34 passes through the jaws and has a threaded end with which a thumb nut 35 engages in order that the jaws may be opened or closed, as desired. The inner 15 face of the jaw 32 is reversely inclined, or in other words, the lower portion inclined upwardly and outwardly, as seen at 36, and then inclines upwardly and inwardly, as seen at 37, and then extends vertically upwardly, as indicated at 38, (see Fig. 1). The inner face of the jaw 33 is constructed in a similar manner to the inner face of the jaw 32, and a detailed description thereof is therefore thought to be unnecessary. One 20 of the shafts 9 or 11, for example, the shaft 9, has loosely mounted thereon a gear 39 fixed to the gear 8 and having a single tooth to engage the pins of a gear 40 suitably mounted and having a single tooth to engage 25 the pins of a gear 41 suitably mounted. The gear 41 has a tooth to engage the actuating lever 42 of a switch 43 which automatically shuts off the current from the source of electric supply to the motor after a predetermined 30 number of revolutions has been made by the motor.

It will, of course, be understood that this 35 automatic stop mechanism may be dispensed with, if desired, and it is not necessary to employ it in all cases arising in practice. When the sharpening rolls are in the position seen in Fig. 4, the razor to be sharpened is not in contact with either sharpening roll.

In the operation, the blade to be sharpened 40 is clamped between the jaws 32 and 33 by proper adjustment of the thumb nut 35. The switch 42 is now actuated in the proper direction to close it, and the motor 2 causes the rolls 12 and 19 to rotate in the direction 45 of the arrows seen in Fig. 2, so that the blade is alternately engaged on opposite sides by the sharpening elements, it being seen that one has the lead on the other. The parts are constructed in such a manner that 50 the blade will be yieldingly pressed against the sharpening surface, due to the resiliency of the arm 31, as will be understood by reference to Fig. 2.

The blade holder is rigidly supported, but 55 owing to the provision of the spring arm 31, it will be maintained against the sharpening elements under the proper tension. This tension can be adjusted, as is apparent, by proper actuation of the thumb nut 28 and 60 vertical adjustment of the blade holder 30,

and by the vertical adjustment of the bracket 25, the machine can be adjusted to receive razor blades of different widths. If it is desired to use different types of sharpening rolls, for example, to substitute a roll having a stropping surface for one having an abrasive or honing surface, it is simply necessary to remove the set collars and insert the rolls to be substituted into position and secure them in position by the set collars.

70 It will be seen from the drawings that the blade holding device is normally positioned in such a manner that the cutting edge of the blade to be sharpened is substantially midway between the shafts 9 and 11. The sharpening surface of the rolls is formed on a radius greater than one-half the distance between the centers of the rolls, and the curvature of the sharpening surface at its end is on a gradually decreasing radius so 85 that the blade returns to its normal neutral position after leaving the sharpening surface without any material vibration.

80 It will now be apparent that I have devised a novel and useful razor sharpening device which embodies the features of advantage enumerated as desirable in the statement of the invention and the above description, and while I have, in the present instance, shown and described a preferred 90 embodiment thereof which will give in practice satisfactory and reliable results, it is to be understood that the same is susceptible of modification in various particulars without departing from the spirit or 95 scope of the invention or sacrificing any of its advantages.

Having thus described my invention, what 100 I claim as new and desire to secure by Letters Patent, is:—

105 1. In a razor sharpening machine, the combination of parallel rotatable sharpening rolls, a bracket arm, and a blade holder having a resilient shank pivotally mounted on the arm to have both a rocking adjustment and an adjustment to and from the rolls in a longitudinal plane passing between the rolls, whereby both the position of the blade with reference to a roll and its resistance to flexure may be varied.

110 2. In a razor sharpening machine, the combination of parallel rotatable sharpening rolls, a bracket arm adjustable to and from the rolls in a plane passing longitudinally between them, and a blade holder having a resilient shank pivotally mounted on the arm to have both a rocking adjustment and an adjustment to and from the rolls in said longitudinal plane, whereby both the position of the blade with reference to a roll and its resistance to flexure may be varied.

115 3. In a razor sharpening machine, the combination of parallel rotatable sharpening rolls, a pivoted bracket arm adjustable to and from the rolls in a plane passing longi- 120 125 130

tudinally between them and also transversely to said plane, and a blade holder having a resilient shank pivotally mounted on the arm to have both a rocking adjustment and an adjustment to and from the rolls in said longitudinal plane, whereby both the position of the blade with reference

to a roll and its resistance to flexure may be varied.

FREDERICK J. KALTEYER.
